UNITED STATES PATENT OFFICE.

JOHN THOMSON, OF NEW YORK, N. Y.

ELECTRIC ZINC-FURNACE WITH INTEGRAL COMPOUND CONDENSER.

1,080,864.

Specification of Letters Patent.

Patented Dec. 9, 1913.

Application filed January 2, 1913. Serial No. 739,792.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Compound Condensers, of which the following is a specification, reference being made to the accompanying drawings, forming a part hereof.

This invention relates to the metallurgy of zinc, having for its object the production of zinc fume by thermo-chemical reaction and then condensing the fume to liquid metal.

A description of the means for attaining the desired results and such an elucidation of the general principles applicable thereto as will clearly disclose the invention will be concurrently pointed out in connection with the description of the accompanying drawings forming a part of this specification and in which drawings there is illustrated one embodiment of the invention.

In said drawings Figure 1 is a transverse center section of a combined furnace and condenser. In the lower or left hand portion of this figure the resistor and charge material have been omitted. Fig. 2 is a half top plan view, as on C, C¹, Fig. 1, and Fig. 3 is a detached sectional diagram along the longitudinal center line B.

This furnace is particularly intended for the reduction of oxid of zinc combined with carbon as the reagent, whereby, when adequately heated the following representative reaction ensues, namely:

If pure ZnO and C are used in precisely correct relative proportions then the answer of the above formula is an exact expression of the result in that all of the charged material would be volatilized as zinc fume and monoxid of carbon and in which case there would be no residue. Such conditions, however, do not obtain in commercial practice as more or less of inert residual matter will remain, depending upon the purity of the materials employed, and thus the formula becomes, as stated, simply representative. Moreover, the presence of a more or less limited amount of residual matter is a cause of difficulty which is encountered in realizing a successful commercial result.

The heat necessary for decomposing the charge is preferably derived from an electric current passed through a broken bed of carbon "resistor," the charge being acted upon by direct conduction of heat.

The bed of carbon resistor H is disposed along the longitudinal center of the furnace, its ends being interpolated between terminals 4 to which the electric current is conducted by copper electrodes 5. This resistor is sustained by a series of spaced grate bars 6 which in turn rest upon ledges, as 7, formed in a shallow tamped casing R. Beneath the grate bars there is a sump n in which the inert residual matter 8 is collected. In the sides 9 of the casing, which confine or form the boundaries of the resistor, are a series of openings, slits or ports 10 whose bottoms extend down to the ledges upon which the grate bars are supported. The tops of the said ports are covered by refractory plates, as 12. Two condensers J, J¹ are employed, each being parallel and immediately adjacent to the side walls of the resistor casing, which in fact provide a part of the inner walls of the condensing chambers.

The resistor carbon is of sufficient depth to fully cover the inner openings of the ports 10. The charge material P is fed to the upper face of the resistor through vertical galleries 13, Fig. 3, formed by a series of spaced slabs or plates 14. The volatilized products of the reaction pass down into and through the transverse zones under the slabs or plates, and from which zones it may flow in various directions through the carbon to the grate bar spaces 15 and thence to the ports as in the manner indicated by the flow arrows 16. The residue may either sift or percolate or be poked down through the resistor and fall into the sump through the grate bar spaces as indicated by the arrows 17. After passing through the bed of carbon resistor the fume and gas will be free of any pernicious oxidizing agent such as CO₂ and will also be at substantially the temperature of the resistor and hence the outflow from the ports 10 into the free spaces e, e¹, of the condensers will maintain a temperature therein approximating that of the side walls of the resistor casing. To realize this condition to the utmost extent the material of the outer walls 18, 18^a of the condensers should be of the best non-heat-conductive refractories and the same

applies to the cover tiles 19 and also the overlying bricks. The latter may furthermore be sheathed with charge material to seal the joints and afford additional heat insulation.

- An advantage of the foregoing construction and arrangement is that the heat necessarily carried away by the fume and gas assists in maintaining the temperature of the resistor casing walls and thus prevents a material direct and additional conduction of heat away from the sides of the resistor itself, and consequently there will be little or no thermal loss from the resistor.
- Moreover, the right and left hand condensers act as thermal "blankets" to the centrally disposed resistor and also aid in maintaining a minimum thermal loss from the resistor.
- The condensation of the clean fume received in the spaces e , e^1 is effected by causing it together with its entraining envelop of CO to pass downwardly through several series of slits or spaces 20 formed by cross-stacked and preferably staggered plates 21 set on edge and arranged longitudinally along and transversely of the condenser chamber casings. These plates usually comprise a large percentage of carbon or graphite and afford a large superficial surface and also provide an ample mass for primarily absorbing heat from the volatilized products of the reaction and then rapidly and progressively conducting away the said heat.

The latter condition is obtained by building the battery of condensing plates upon a series of supports 23 that are partially immersed in a bath of liquid zinc 24 which is maintained at about a constant depth in the bottom of the condensing chamber and the temperature of which bath is under control. The temperature of the said bath is controlled according to the rate of evolution of fume and gas by causing a circulation of hot gases or of cooling air, as the need may be, through the chambers or flues Y , Y^1 , situated beneath the condensers. The thermal conditions may be illustrated by assuming a case, thus: The bath must be maintained at a safe temperature above its "freezing" point which is about 785° F. Let this temperature of the bath be taken as 850° F. Now, if the fume and gas in the spaces e , e^1 , as they enter the slits has a temperature of say 2300° F. and if the upper edges of the plates have a temperature of say 2200° F. then there will be a difference of 1350° F. between the upper series of plates and the portions of the supports 23 which are immersed in the bath. As it will be sufficient if the fume and gas is chilled to a temperature of say 1050° F. this means a drop of 1250° and leaves a reserve chilling difference in the condenser of 100° F. between

the upper plates and the top of the bath. The final exit of any residual fume and the original CO from the lower series of plates is in the form of narrow sheets, which impinge directly upon the surfaces of the baths and which react and flow right and left to subsequently find egress through the openings or ports 25, 26, into the large chamber or flue X beneath the resistor, thence to atmosphere by a tube or tubes 27. During the slow transit through the large chamber X the stored heat in the gas acts to conserve the temperature in the sump.

The condenser plates may be narrow or wide, thick or thin, and set to provide slits of any desired width, but it is desirable that the aggregate area of the slits shall be such as to insure a low velocity of flow thereof through. The spacing of the longitudinal and transverse plates may be such as to obtain an equal flow area through each series or the velocity may be more rapid through one series than the other. If the flow area is uniform from top to bottom the velocity of flow will constantly diminish, due to the reduction of volume as the temperature lowers, hence the plates may be stacked so that the spaces between them will be lessened and so that the number or thickness of the plates in a series may be increased progressively downward.

In a design having a central resistor combined with compound condensers it is advisable and quite essential that the evolved products of the reaction shall have a primary free escape from the seat or seats of the reaction, that the heat developed in the resistor shall be largely utilized precisely at the seat or seats of the reaction, that volatilized products of the reaction shall be delivered into the condensers in such manner as to insure a uniform dispersion of volume and flow through the condensing system, that the velocity of flow imparted to the fume and gas shall be relatively slow, that a large or objectionable "back-pressure" of fume and gas shall not be set up against the seat or seats of the reaction and that the means for absorbing and dissipating the stored heat in the fume and gas shall be adaptable to the rate at which they are evolved. These features, jointly and severally, are herein fully disclosed, but it is manifest that the improvements herein set forth are not limited to the precise construction and arrangement shown and described, as they may be embodied in various forms and modifications, and that various changes and alterations in the manner and method of working may be made without departing from the spirit and essence of the invention.

What I claim is:

1. In an electric smelting furnace, a bed-of-carbon resistor supported on a grate

- above an underlying residue sump and located between confining side walls having a series of lateral openings or ports leading to condensers on opposite sides of the resistor.
5. 2. An electric zinc smelting furnace having a bed-of-carbon resistor supported on spaced grate members above a residue sump, condensers located on opposite sides of the resistor, a resistor resting side wall providing a part of the inner wall of the condenser and having openings therein through which fumes can pass directly from the resistor to the condensers.
10. 3. A combined electric furnace and condenser having a resistor, resistor retaining walls contiguous to the sides of the resistor, said walls being provided with openings through which fumes can pass directly from the resistor to the upper portion of the condensers which are arranged on opposite sides of the resistor.
15. 4. An electric furnace having a resistor supported on spaced grate bars below which is a sump, the resistor being retained in place by walls having therein openings for conducting the fumes and gases to a condenser or condensers, the top portions of said openings being below the top of that portion of the resistor adjacent thereto and the lower portion of said openings communicating with the space between the grate bars whereby any fumes or gases which pass through the resistor to the space between the grate bars can flow directly through said openings to the condenser or condensers.
20. 5. In an electric zinc smelting furnace, a resistor casing having a series of resistor supporting spaced grate bars and perforated side walls which form a part of the walls of condensers along the sides of the said casing.
25. 6. In an electric furnace of the resistor type, resistor casing side walls having transverse ports, the upper portions of the inner portions of which are partially closed by the broken carbon of the resistor and the lower portions of the inner portions of which ports face the spaces between the grate bars.
30. 7. In an electric zinc smelting furnace, a bed-of-carbon resistor sustained by a grate contained in a casing having perforated side walls and connecting spaces along the outer sides of said walls for receiving the volatilized products of the reaction after they will have passed through the said resistor.
35. 8. A condenser combined with a suitable source of supply of zinc fume or of fume and gas, said condenser having a battery of spaced cross stacked and staggered plates sustained by supports at least partially immersed in a bath of liquid metal.
9. An electric zinc furnace adapted to effect the reaction of $ZnO + C$, and side condensers for receiving the volatilized products of the reaction and provided with cross-stacked plates set edgewise to the direction of the flowing fume and gas.
10. In an electric zinc furnace, a resistor having subdivided zones through which the volatilized and the inert products of the reaction respectively flow and gravitate, combined with perforated side walls forming portions of the inner walls of condensing chambers, a series of spaced grate bars and an underlying sump.
15. 11. In a furnace and condenser, a resistor for effecting substantially the $ZnO + C$ reaction, the volatilized products thereof being passed into and through the said resistor, combined with one or more condensers comprising a system of heat absorbing and heat conducting plates, the upper portions of which have a temperature approximating that of the fume and gas and the lower portions of which have a temperature approximating that of liquid zinc.
20. 12. A combined electric furnace and condenser having a resistor above a sump, condensers on opposite sides of the resistor arranged to receive in the upper portions thereof the products of the reaction, and a chamber or chambers below the sump into which the residual gases from the condenser pass prior to their exit to the atmosphere.
25. 13. A zinc condensing apparatus having a plurality of condensing chambers provided therein with spaced cross stacked members located over baths of molten zinc so that fumes passing downwardly through said stack will impinge against the top surface of the bath, and a chamber under the sump for receiving the residual gases from the condensing chambers.
30. 14. A zinc condenser having a plurality of condensing chambers provided with liquid baths at the bottom, a common chamber into which the residual gases from the condensers flow and provided with a common cooling or heating means below the liquid baths.
35. This specification signed and witnessed this 31 day of December A. D. 1913.
